DESIGN FOR A COMBINED COMB AND COMB CLEANING BRUSH

Henry M. Pernini, Chicago, Ill.

Application September 25, 1945, Serial No. 122,327

Term of patent 7 years

(Cl. D86—8)

To all whom it may concern:

Be it known that I, Henry M. Pernini, a citizen of the United States, residing at Chicago, in the county of Cook and State of Illinois, have invented a new, original, and ornamental Design for a Combined Comb and Comb Cleaning Brush, of which the following is a specification, reference being had to the accompanying drawing, forming a part thereof.

and comb cleaning brush, showing my new design;

I claim:

The ornamental design for a combined comb and comb cleaning brush, substantially as shown.

HENRY M. PERNINI.
